UNITED STATES PATENT OFFICE.

PRESTON L. BLAKE, OF AMARILLO, TEXAS.

TYPEWRITER COPYHOLDER AND LINE MARKER.

Application filed January 20, 1925. Serial No. 3,619.

This invention relates to copy holders, and especially an improved combination of typewriter-copy holder and line marker.

- The main objects of this invention are to provide an exceedingly capacious, strong, durable, elastic, convenient and thoroughly practical device for holding large and heavy books, as well as smaller ones and single sheets, to be copied from by a typist; to provide a device of this kind that also holds the typewriter being used for copying; to combine such device with the typewriter for holding the copy in a definite fixed and convenient position above the typewriter; to combine therewith a very simple, convenient and practical line marker; and to construct a combined device of this character that is comparatively simple and capable of being manufactured at a relatively low cost.
- 20 A further object is to provide a device of this kind that has uprights or frame elements so constructed of ordinary mercantile stock, strips or bars of metal, that its lower part is relatively stiff and rigid, while its upper part has sufficient elasticity to avoid permanent distortion of the device in the event a heavy book is allowed to drop a slight distance onto the copy-seat.

Other objects and important features will be pointed out or implied in the following details of description, in connection with the accompanying drawings in which:

Fig. 1 is a front view of the device; Fig. 2 is a left-side view, the typewriter-frame and copy-sheet being indicated in broken lines; and Fig. 3 is an enlarged detail view in section along the lines 3—3, 3—3, of Figs. 1 and 2.

According to the embodiment of the invention here shown, a board or base-plate 5 is provided with grooves 6 in which are seated the horizontal parts 7 of strips of steel or other metal whose upright parts 8 are riveted to or otherwise rigidly united with uprights 9 that are also formed of strips of steel or other somewhat springy metal or material. The lower end of each part 9 extends horizontally forward and is riveted or otherwise secured to the part 7, as shown at 10, and the part 11 of each upright is forwardly and downwardly inclined from the part 8 to the part 10 so as to form a brace at the corner or angular bend where the parts 7 and 8 unite. Screws, as indicated, or other appropriate means may be employed for securing the parts 7 in the

grooves 6, for rigidly uniting the base-plate or typewriter-seat with the metal strips that support the copy-seat and line marker.

The uprights 8 are bowed and forwardly 60 extended at 12, and each part 12 merges with a forwardly and downwardly inclined part 13 that terminates at 14 or there merges with a forwardly and upwardly inclined part 15. Each part 15 terminates at an upward extension 16 of the strip that includes parts 7, 8, 12, 13 and 15.

Each part 9 merges with a bowed or forwardly extended part 17 whose front end is riveted or otherwise secured to the part 13. 70 The parts 12 and 17, being bowed and of springy material, act as shock-absorbers in the event a heavy book is dropped into the book-seat or copy-seat. Although the parts 13, 14 and 15 would form a copy-seat if unobstructed, I preferably provide a sheet metal copy-seat comprising a forwardly and downwardly inclined plate 18, a forwardly and upwardly inclined plate 19, and an up-standing flange 19^a these plates and flange 80 being preferably integral with one another. The parts 18 and 19^a are riveted or otherwise secured to the parts 12, 13 and 16; and the part 19^a not only serves as a stop to prevent the edges of book leaves from swinging 85 to the closed or anti-reading position, but also adds rigidity to the front edge of the copy-seat. The copy is indicated at C as a single sheet, but it is obvious that a book of large size and of more than 90 average thickness can be placed, while open, between the parts 13 and 19^a, and that the latter will serve to prevent the book-leaves from swinging forward.

The parts 9, 10 and 11 have a plate 20 95 riveted or otherwise secured thereon, and an upwardly extending flange 21 combines with the other parts of the plate 20 to form a channel for receiving the lower rear edge of the typewriter-frame. A pad 22, of rubber or other compressible and elastic material, such as felt or the like, may be secured to or fitted in the channel of the plate 20, and when the rear edge of the typewriter T is embedded in this pad, as shown, it is not only secured against accidental shifting with relation to the copy-seat, but also serves to deaden the sound of the typewriter.

In addition to the uses of the plates 18, 19 and 20, as defined in the foregoing, they 110 rigidly unite the pairs of strips, defined above, so they remain rigidly united even

if the base or plate 5 is detached or substituted by other means of securing the copy seat in a definite relation to the typewriter.

Most all of the structure defined in the foregoing is described and claimed in an application filed by me on or about the 15th day of December, 1923, Serial No. 680,913, entitled "Typewriter copy holder"; and I will now give further details of the improvements which include the line marker, mentioned in the foregoing:

Guiding and supporting strips 23 and 24 are preferably riveted or bolted to the parts 12 and 15, and have apertured ends extending laterally beyond the edges of the strips that support the copy-seat, their apertures 23^a and 24^a being rectangular or non-cylindrical and preferably oblong. Through a pair of these apertures extends a compound adjusting bar 25, consisting of an intermediate part 25^a, an upper end part 25^b, and a lower end part 25^c, these latter parts extending at right angles to and from opposite ends of the intermediate part, in opposite directions, and lying in parallel planes. The shape of this bar may be defined either as a compound curve or a compound angle, so the nomenclature "compound bar" appears appropriate. The lower part 25^c is serrated or provided with a series of evenly spaced notches at 26, the spaces or pitch of these notches being preferably equal to the "single spacing" of an ordinary typewriter. These notches engage alternately or alternatively with the adjacent part of the bar 24, and a handle 27 is provided on its lower end for interchanging these notches with the bar 24, thereby adjusting this bar for properly positioning its arm or line-index 28 with respect to the copy C.

For properly adjusting the arm 28 with respect to the different forms of copy, towards and from the plate 18, the index-arm or line-index may be angularly bent at 29, and its attaching end may be apertured and screw-threaded at 30, to receive and mesh with an attaching and adjusting screw 31 having a knurled head or handle 32. The shank of this screw extends through an aperture of the part 25^a and works freely in this aperture which is not screw-threaded. It will be seen, therefore, that by loosening the screw 31, the arm 28 is freed so that it can be adjusted to any of the positions shown in full and broken lines and to an infinite number of other positions; and that by tightening the screw, the arm 28 is secured in any one of its adjusted positions.

Although the inclined position of the part 24, and of the part 25^c in the opposite direction, tend to utilize the force of gravity for holding the respective notches 26 in engagement with the bar 24, and although it is within the scope of this invention to change the shape of each notch so that such

engagement will effectually be retained until the bar is manually moved for disengaging these parts and changing the adjustments of the bar and its arm 28, it may be of advantage to provide a spring for yieldingly retaining the engagement of these parts, and such a spring is indicated at 33 of Fig. 3, being omitted in the other figures of the drawings.

For use in connection with certain types of typewriters, it may be desirable to operate the line-marker with the left hand, instead of the right, and in such event, the bar 25 may be transferred from the position shown to the apertured parts 23^a and 24^a at the left side of the device, and the arm 28 may be transferred from the left side to the right side of the bar 25. One or more rollers (not shown) may be journaled on the arm 28 for rolling on the copy or on the plate 18.

In operating the line marker when the copy C is on the copy-seat, the index-arm 28 is first adjusted so it lies near the copy and just below the first line to be copied from, and when through with this line, the operator grasps the handle 27 and pulls it forward, then allows it to descend until the index-arm is just below the next succeeding line, then engages the notched part 26 with the bar 24 for holding the line-marker in position; and this operation is repeated until all the lines have been successively marked and copied or copied from.

It is not intended to limit my patent protection to the exact details of construction and arrangement here shown, but the inventive idea includes analogous devices within the scope of the claims.

What I claim as my invention is:

1. A copy holder which includes two spaced pairs of relatively thin and wide springy strips, the strips of each pair having their wide sides confronting one another, a horizontal plate to be seated on a table and to extend under a typewriter, a copy-holding plate, and means securing the copy-holding plate to the spaced pairs of strips over said horizontal plate, said strips of each pair including horizontally extending parts which are superposed upon one another and upon said horizontal plate, and secured to the latter, said strips having juxtaposed parts fixedly secured to one another at points above said horizontal plate and thus forming relatively stiff upright supporting parts, the parts of said strips which extend up from said stiff upright parts to said copy-holding plate being forwardly and downwardly bowed and spaced from one another to provide a springy support for said copy-holding plate.

2. The combination of a copy seat including an upright part against which the back of a copy can rest, a supporting structure

holding the copy-seat in position to permit a typewriter to be positioned under the copy-seat, this supporting structure including apertured elements, a bar including a serrated part and being slideable up and down in said apertured elements and adjustable to different positions by interchangeable engagement of the serrations with one of said apertured elements, and a line-index arm 10 carried by said bar, substantially as shown, for the purpose specified.

3. The structure defined by claim 2, said arm being adjustable towards and from said upright part, and manipulative means

to secure said arm in its different adjustments.

4. The structure defined by claim 2, one of said apertured elements being above and in rear of the other, said bar having its intermediate part crossing the plane in which lies the said upright part of the copy-seat, the parts that slide in said apertured elements extending in planes in front and in rear of the first said plane and substantially parallel therewith.

In testimony whereof I affix my signature

PRESTON L. RLAKE.
